BOTTLE HOLDING STAND

Harold Brandeis, Skokie, Ill.

Application February 27, 1956, Serial No. 40,350

Term of patent 7 years

(Cl. D58—26)

Fig. 1 is a top plan view of a bottle holding stand, showing my new design;

Fig. 2 is a side elevational view thereof;

Fig. 3 is a front view thereof; and

Fig. 4 is a rear view thereof.

The bottle shown in broken lines in Figs. 1 to 4 is for illustrative purposes only.

I claim:

The ornamental design for a bottle holding stand, substantially as shown and described.
